UNITED STATES PATENT OFFICE

MORRIS KLINE, OF CLEVELAND HEIGHTS, OHIO

ENVELOPE FILE OR THE LIKE

Application filed November 30, 1928. Serial No. 322,824.

This invention had its conception in the thought of providing a convenient file for returned checks or vouchers and in which the envelopes, wherein the checks or vouchers are mailed or delivered each month by the bank, are utilized as parts of the file. From the following description, however, it will be obvious that the invention is susceptible to a much wider range of use.

10 The primary purpose of the invention is to provide a file comprising a receiver or cover, in the nature of a so-called "loose-leaf binder", incorporating anchorage elements, such as filing posts, rings, or their equivalents, and a 15 plurality of attaching devices by means of which envelopes may be readily connected to the anchorage elements.

In the event the file is used for return checks or vouchers, as originally intended, the 20 receiver or cover may be of such a capacity as will accommodate twelve full envelopes and be equipped with a corresponding number of attaching devices. With each receiver or cover, marked with the year, may be supplied a series of stickers bearing the names 25 of the months, so that each envelope may be labeled to indicate the month to which its contents belong.

Other objects of the invention are to provide, in combination with a suitable receiver 30 or cover having anchorage elements, very simple and inexpensive attaching devices that may be readily applied to standard envelopes for connecting them in an especially facile 35 manner to the anchorage elements.

Several embodiments of the invention are illustrated in the accompanying drawings which constitute a part hereof and, with reference thereto, Fig. 1 is a perspective view of 40 an envelope file embodying the invention; Fig. 2 is a fragmentary longitudinal section through the file, a part of the envelope appearing in the view being torn away to better reveal the associated attaching device; Fig. 3 is a sectional detail on the line 3—3 of 45 Fig. 2; Fig. 4 is a fragmentary longitudinal section through a file to whose binding posts is connected an envelope by means of another form of the attaching device.

50 The receiver or cover is designated gener-

ally by the reference numeral 1 and it may be of any desired construction and of any suitable material. In the present instance the receiver or cover is made of a single piece of flexible material, such as leather, or a good 55 quality of imitation leather. On each side of a back portion 2 the material is folded inwardly and then back upon itself to provide reentrant portions 3, and anchorage elements or binding posts 4, which may be any 60 of the well known types suitable for the purpose, are supported by and between the reentrant portions 3. The material is extended beyond the reentrant portions 3 to form covers that are designated 5. 10 denote envelopes which may be of standard design and 65 construction. They are preferably of heavy tough paper, and may be like those used by banks for returning paid checks or vouchers to depositors. The envelopes are adapted to 70 be connected to the anchorage elements 4 by means of attaching devices which, in the embodiment illustrated in Figs. 1, 2 and 3, are designated 11 and consist of pieces of resiliency wire that are shaped at their ends to 75 form loops 12 and hooks 13, the latter being designed to embrace the anchorage elements 4.

To connect an envelope to a receiver or cover 1 by means of an attaching device 11, 80 the envelope is cut or torn to form, adjacent the ends of its side remote from the flap 14, slits 15, and the attaching device is then inserted into the envelope so that the hooks 13 extend through the slits 15. The hook 13 at 85 one end may then be engaged beneath one of the anchorage elements 4 while the hook at the opposite end is sprung inwardly, as indicated by dotted lines in Fig. 2, so that it can be passed beneath the other anchorage 90 element, the resiliency of the wire causing the hook to engage beneath the anchorage element when released. The loops 12, by contact with the folded ends of the envelope, prevent the envelope from shifting longitudinally of the attaching device to any appreciable extent.

By the means above described a plurality of envelopes may be easily and quickly connected to the receiver or cover and each may 100

be removed and inserted without the necessity of disturbing any of the others.

It is obvious that any sort of an anchorage element may be used with the present form of attaching device so long as it will properly cooperate with the hooks 13, and, in the case at hand, the anchorage element may be permanently secured to the receiver or cover since it is not necessary to remove the same in connecting and disconnecting the envelopes.

In Fig. 4, the attaching device 11^c is shown again as constructed of a piece of wire that is formed at its ends to provide rings 13^c for application to the anchorage elements 4, said rings being extended through holes or slits 15^c that are produced by tearing or cutting off the corners of the envelope.

Having thus described my invention, what I claim is:—

1. In combination, a receiver incorporating spaced-apart anchorage elements, an envelope provided with similarly spaced openings in one of its folded edges, and a member adapted to be inserted within the envelope and having parts arranged to be extended through said openings and that are adapted to be engaged with and disengaged from the anchorage elements by movements, two of which are longitudinally of said member with respect to said elements.

2. In combination, a receiver incorporating spaced-apart anchorage elements, an envelope provided with similarly spaced openings in one of its folded edges, an attaching device inserted within the envelope and having parts extending inwardly of said envelope for engagement with parts of the envelope to prevent longitudinal movement of the latter with respect to the device and other parts arranged to extend outwardly through said openings for cooperation with the anchorage elements.

3. In combination, a receiver incorporating spaced-apart anchorage elements, an envelope provided with similarly spaced openings in one of its folded edges, an attaching device inserted within the envelope and consisting of a wire whose ends are so shaped as to form loops for engagement with the inner surfaces of the ends of the envelope and other parts that are arranged to extend through said openings for holding engagement with the anchorage elements.

4. In combination, a receiver incorporating spaced-apart anchorage elements, an envelope provided with similarly spaced openings in one of its folded edges, an attaching device inserted within the envelope and consisting of a wire whose end portions are so shaped as to form loops for engagement with the ends of the envelope and whose extremities are extended through said openings and formed into hooks for holding engagement with the anchorage elements, said hooks

yielding with respect to the body portion of the device to permit of their connection with and disconnection from said elements.

5. In combination, a receiver incorporating spaced anchorage elements, an envelope having openings at the ends of its side remote from its flap, and a wire adapted to fit within said envelope and formed at its ends to extend through said openings and having holding engagement with said anchorage elements and to so cooperate with contiguous parts of said envelope as to prevent longitudinal movement of the envelope on said wire.

6. In combination, a receiver incorporating spaced anchorage elements, an envelope having openings at the ends of its side remote from its flap, and a wire adapted to fit within said envelope and formed at its ends to extend through said openings and to loop around said anchorage elements and to so cooperate with contiguous parts of said envelope as to prevent longitudinal movement of the envelope on said wire.

In testimony whereof, I hereunto affix my signature.

MORRIS KLINE.
